UNITED STATES PATENT OFFICE.

VAN BUREN LAMB, OF NEW HAVEN, CONNECTICUT, ASSIGNOR TO
KEYSTONE BRAKE-SHOE COMPANY, OF NEW YORK, N. Y., A
CORPORATION OF NEW YORK.

BRAKE.

No. 841,694.

Specification of Letters Patent.

Patented Jan. 22, 1907.

Application filed May 26, 1906. Serial No. 318,809.

To all whom it may concern:

Be it known that I, VAN BUREN LAMB, residing at New Haven, in the county of New Haven and State of Connecticut, have invented certain new and useful Improvements in Brakes, of which the following is a full, clear, and exact description, such as will enable others skilled in the art to which it appertains to make and use the same.

10 This invention relates to brakes.

One of the objects thereof is to provide braking mechanism of increased simplicity and durability of construction.

Another object is to provide means of the 15 above type in which the metal is economically consumed.

Another object is to provide means of the above type in which the component members are readily taken apart and reassembled.

20 Other objects will be in part obvious and in part pointed out hereinafter.

The invention accordingly consists in the features of construction, combinations of elements, and arrangement of parts which 25 will be exemplified in the embodiment thereof hereinafter described and the scope of the application of which will be indicated in the following claims.

30 In the accompanying drawings, wherein is shown one of the various possible embodiments of this invention, Figure 1 is a side elevation thereof. Fig. 2 is a rear view of parts shown in Fig. 1. Fig. 3 is a perspective view of a portion of a head. Fig. 4 is a similar 35 view of another portion of a head.

Similar reference characters refer to similar parts throughout the several views of the drawings.

40 Referring now to Fig. 1 of the drawings, there is shown a brake-head 1, comprising the main and auxiliary portions 2 and 3, respectively forming the subject-matter of Figs. 3 and 4 of the drawings.

45 Portion 2 comprises a body portion having formed thereon the means 4 whereby the head is mounted upon the brake-beam or other supporting member. Portion 2 is provided with a side flange or web 5 upon one side of the head and upon the other 50 side with a short flange or abutment 6, the function of which will be hereinafter described. Extending laterally from portion 2 is a projection 7 of tapering form and pro-

vided with a keyway 8, and likewise extending in a general lateral direction from this portion of the head are the end shoulders 9, recessed as shown at 10.

The auxiliary or complementary portion 3 of the head (shown in Fig. 4 of the drawings) is provided with a side web 11, adapted to fit beneath the abutment 6 upon portion 2 and rest within the recesses 10. The positioning of the parts in this relation is brought about by thrusting the portion 3 toward the portion 2, the projection 7 passing through a suitable recess or mortise 12 formed in the former portion.

Portions 2 and 3 are collectively provided with a recess 13, having undercut walls converging toward each end of the head and of decreasing depth in these directions, as is best shown in Fig. 1 of the drawings.

70 The shoes 14 used with the above head are preferably divided transversely into two portions 15 and 16 and are provided upon their rear surfaces with tenons adapted, with the parts in assembled relation, to fit closely the recess or mortise 13, formed within the forward face of the head, as above described. Each shoe is, moreover, provided upon its forward face or the face toward the wheel with a mortise which is the counterpart of the tenon immediately above mentioned and receives therein the similar tenon upon another shoe member 17, transversely divided 75 at a point offset with respect to the point of division of the shoe first mentioned.

80 The method of use of the above-described embodiment of this invention is substantially as follows: Assuming the parts to be in the condition shown in Fig. 1 of the drawings and assuming that the wear upon the double shoe has extended to a point within the shoe member 14, such wear being permitted without dropping of the parts by reason of the dovetailed conformation of the joint between the shoe members, the portions of the head are laterally separated, as by withdrawing the spring-key 18, which 85 normally holds these parts snugly together, and removing the portions of the worn shoe. These portions are then fitted within the 90 portions of a new shoe identical with that removed in its original form, and the tenon upon the rear surface of the new shoe is fitted 95 within the head and the parts reassembled 100. 105

in a manner which will be clear from the drawings, taken in connection with the above description.

It will thus be seen that there is provided a simple construction in which the several objects of this invention are attained. The metal of each shoe is entirely consumed, quite doing away with the scrapping of parts or the dropping of the same upon the road-bed, and yet all parts of the braking device are rigidly held in assembled condition. The strength of this assemblage of parts will be obvious from a consideration of their interfitting nature, whereby dependence upon retaining devices is substantially done away with. The parts, moreover, are readily taken apart by the removal of the key and may be quickly reassembled, all without the use of special tools.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. It is also to be understood that the language used in the following claims is intended to cover all of the generic and specific features of the invention herein described and all statements of the scope of the invention which as a matter of language might be said to fall therebetween.

Having described my invention, what I claim as new, and desire to secure by Letters Patent, is—

1. In construction of the class described, in combination, a brake-shoe having upon its rear surface a projecting portion the lateral walls of which are undercut, a second brake-shoe fitted about said projecting portion and provided upon its rear surface with a similar projecting portion, a brake-head comprising two laterally-separable portions each of which is adapted to fit one of the lateral walls of said last-mentioned projecting portion adjacent each end thereof, one of the portions of said brake-head being provided with a projection extending through the other portion of said head, and means adapted to hold the portions of said head in assembled relation.

2. In construction of the class described, in combination, a brake-shoe having upon its rear surface a projecting portion of decreasing thickness toward the ends of the shoe and the lateral walls of which are undercut, a second brake-shoe fitted about said projecting portion and provided upon its rear surface with a similar projecting portion, a brake-head comprising two laterally-separable portions each of which is adapted to fit one of the lateral walls of said last-mentioned projecting portion adjacent each end

thereof, one of the portions of said brake-head being provided with a projection extending through the other portion of said head, and means adapted to hold the portions of said head in assembled relation. 70

3. In construction of the class described, in combination, a brake-shoe having upon its rear surface a projecting portion the lateral walls of which are undercut and converge toward the ends of the shoe, a second brake-shoe fitted about said projecting portion and provided upon its rear surface with a similar projecting portion, a brake-head comprising two laterally-separable portions each of which is adapted to fit one of the lateral walls 80 of said last-mentioned projecting portion adjacent each end thereof, one of the portions of said brake-head being provided with a projection extending through the other portion of said head, and means adapted to hold the portions of said head in assembled relation. 85

4. In construction of the class described, in combination, a brake-shoe provided upon its rear surface with a projecting portion the lateral walls of which are undercut and converge toward each end of the shoe, a brake-head comprising two laterally-separable portions each of which is adapted to fit one of the lateral walls of said projecting portion adjacent each end thereof, one portion of said brake-head being provided with a projection passing through the other portion thereof, and means adapted to hold the portions of said head in assembled condition. 90

5. In construction of the class described, in combination, a brake-shoe provided upon its rear surface with a projecting portion of decreasing thickness toward the ends of the shoe and the lateral walls of which are undercut and converge toward each end of the shoe, a brake-head comprising two laterally-separable portions each of which is adapted to fit one of the lateral walls of said projecting portion adjacent each end thereof, one portion of said brake-head being provided with a projection passing through the other portion thereof, and means adapted to hold the portions of said head in assembled condition. 105

6. In construction of the class described, in combination, a brake-shoe provided upon its rear surface with a projecting portion of decreasing thickness toward the ends of the shoe and the lateral walls of which are undercut, a brake-head comprising two laterally-separable portions respectively fitting said lateral walls adjacent each end thereof, one of said portions of said head being provided with a projection extending through the other portion of said head, and means holding the portions of said head in assembled condition. 110

7. In construction of the class described, in combination, a brake-shoe having upon its 130

5 rear surface a projecting portion the lateral walls of which are undercut, a second brake-shoe fitted about said projecting portion and provided with a similar projecting portion upon its rear surface, a brake-head comprising two laterally-separable portions each of which is adapted to fit one of the undercut surfaces adjacent each end thereof, one of the portions of said head being provided with 10 laterally-extended ends between which the other portion of said head is fitted, and means adapted to hold the portions of said head in assembled condition.

8. In construction of the class described, 15 in combination, a brake-shoe having upon its rear surface a projecting portion the lateral walls of which are undercut and converge toward each end of the shoe, a second brake-shoe fitted about said projecting portion and provided with a similar projecting portion upon its rear surface, a brake-head comprising two laterally-separable portions each of which is adapted to fit one of said undercut surfaces adjacent each end thereof, one of the 20 portions of said head being provided with laterally-extended ends between which the other portion of said head is fitted, and means adapted to hold the portions of said head in assembled condition.

25 9. In construction of the class described, in combination, a brake-shoe provided upon its rear surface with a projecting portion the lateral walls of which are undercut and converge toward each end of the shoe, a brake-head comprising two laterally-separable portions adapted respectively to fit said undercut surfaces adjacent each end thereof, one portion of said head being provided with laterally-extending ends and a laterally-extending 30 central portion, and the other portion of said head being adapted to fit between said ends and under said central portion, and means adapted to hold the portions of said head in assembled condition.

40 10. In construction of the class described, in combination, a brake-shoe provided upon its rear surface with a projecting portion the lateral walls of which are undercut, a brake-head comprising two laterally-separable portions adapted respectively to fit said undercut walls adjacent each end thereof, one of 45 said portions of said head being provided with a projection extending through the other portion thereof, and means adapted to hold the portions of said head in assembled condition.

50 11. In construction of the class described, in combination, a brake-shoe provided upon its rear surface with a projecting portion the lateral walls of which are undercut, a brake-head comprising a pair of laterally-separable portions adapted respectively to fit said undercut walls adjacent each end thereof, one of the portions of said head being provided 55 with laterally-extended ends between which

the other portion is adapted to fit, and means adapted to hold the portions of said head in assembled condition.

12. In construction of the class described, in combination, a brake-shoe provided upon its rear surface with a projecting portion the lateral walls of which are undercut, a brake-head comprising two laterally-separable portions each of which is adapted to fit one of said undercut surfaces adjacent each end thereof, one portion of said head being provided with laterally-extended ends and a laterally-extended central portion, and the other portion of said head being adapted to fit between said ends and under said central portion, and means adapted to hold the portions of said head in assembled condition.

13. In construction of the class described, in combination, a brake-shoe provided upon its rear surface with a projecting portion the lateral walls of which are undercut, a brake-head comprising two laterally-separable portions adapted respectively to fit said undercut walls adjacent each end thereof, one of said portions of said head being provided with a projection extending through the other portion thereof, and a key passing through said projection and adapted to hold the portions of said head in assembled condition.

14. In construction of the class described, in combination, a brake-shoe provided upon its rear surface with a projecting portion the lateral walls of which are undercut, a brake-head comprising two laterally-separable portions adapted respectively to fit said undercut walls adjacent each end thereof, one of said portions of said head being provided with a projection extending through the other portion thereof, and a spring-key passing through said projection and spaced from said head and resting against the lateral surfaces thereof adapted to hold the portions in assembled condition.

15. In construction of the class described, in combination, a brake-shoe having upon its rear surface a projecting portion the lateral walls of which are undercut, a second brake-shoe fitted about said projecting portion and provided upon its rear surface with a similar projecting portion, a brake-head comprising two laterally-separable portions each of which is adapted to fit one of the lateral walls of said last-mentioned projecting portion adjacent each end thereof, one of the portions of said brake-head being provided with a projection extending through the other portion of said head and one portion of said head being provided with laterally-extended ends between which the other portion is adapted to fit, and means adapted to hold the portions of said head in assembled condition.

16. In construction of the class described, in combination, a brake-shoe provided upon its rear surface with a projecting portion the

- lateral walls of which are undercut and converge toward each end of the shoe, a brake-head comprising two laterally-separable portions each of which is adapted to fit one of the lateral walls of said projecting portion adjacent each end thereof, one portion of said brake-head being provided with a projection passing through the other portion thereof and one portion of said head being provided with laterally-extended ends between which the other portion is adapted to fit, and means adapted to hold the portions of said head in assembled condition.
17. In construction of the class described, in combination, a brake-shoe provided upon its rear surface with a projecting portion of decreasing thickness toward the ends of the shoe and the lateral walls of which are undercut and converge toward each end of the shoe, a brake-head comprising two laterally-separable portions each of which is adapted to fit one of the lateral walls of said projecting portion adjacent each end thereof, one portion of said brake-head being provided with a projection passing through the other portion thereof and one portion of said head being provided with laterally-extended ends between which the other portion is adapted to fit, and means adapted to hold the portions of said head in assembled condition.
18. In construction of the class described, in combination, a brake-shoe having upon its rear surface a projecting portion the lateral walls of which are undercut, a second brake-shoe fitted about said projecting portion and provided upon its rear surface with a similar projecting portion, a brake-head comprising two laterally-separable portions each of which is adapted to fit one of the lateral walls of said last-mentioned projecting portion adjacent each end thereof, one of the portions of said brake-head being provided with a projection extending through the other portion of said head and one portion of said head being provided with laterally-extended ends and a laterally-extended central portion, the remaining portion of said head being adapted to fit between said ends and under said central portion, and means adapted to hold the portions of said head in assembled condition.
19. In construction of the class described, in combination, a brake-shoe having upon its rear surface a projecting portion the lateral walls of which are undercut, a second brake-shoe fitted about said projecting portion and provided upon its rear surface with
- a similar projecting portion, a brake-head comprising two laterally-separable portions each of which is adapted to fit one of the lateral walls of said last-mentioned projecting portion adjacent each end thereof, one of the portions of said brake-head being provided with a projection extending through the other portion of said head and one portion of said head being provided with laterally-extended ends and a laterally-extended central portion, the remaining portion of said head being adapted to fit between said ends and under said central portion, and a key passing through said projection adapted to hold the portions of said head in assembled condition.
20. In construction of the class described, in combination, a brake-shoe having upon its rear surface a projecting portion the lateral walls of which are undercut, a second brake-shoe fitted about said projecting portion and provided upon its rear surface with a similar projecting portion, each of said shoes being transversely divided into two parts, a brake-head comprising two laterally-separable portions each of which is adapted to fit one of the lateral walls of said last-mentioned projecting portion adjacent each end thereof, one of the portions of said brake-head being provided with a projection extending through the other portion of said head, and means adapted to hold the portions of said head in assembled relation.
21. In construction of the class described, in combination, a brake-shoe having upon its rear surface a projecting portion the lateral walls of which are undercut, a second brake-shoe fitted about said projecting portion and provided upon its rear surface with a similar projecting portion, each of said shoes being transversely divided into two parts on lines offset with respect one to another, a brake-head comprising two laterally-separable portions each of which is adapted to fit one of the lateral walls of said last-mentioned projecting portion adjacent each end thereof, one of the portions of said brake-head being provided with a projection extending through the other portion of said head, and means adapted to hold the portions of said head in assembled relation.

In testimony whereof I affix my signature in the presence of two witnesses.

VAN BUREN LAMB.
